APPARATUS FOR CAPS FOR SHOES

Friedrich Gamerdinger, Zuffenhausen, and Otto
Weber, Stuttgart, GermanyApplication May 27, 1935, Serial No. 23,636
In Germany May 31, 1934

8 Claims. (Cl. 91—46)

This invention relates to apparatus for treatment of material used in forming caps for shoes or the like.

An object of this invention is to provide an apparatus which is so constructed that material used in forming caps for shoes may be treated in such a manner that a uniform treatment is had for specified kinds of material.

Another object of this invention is to provide a method of material treatment whereby the material is initially immersed in a treating liquid and maintained in the liquid for a predetermined length of time and then withdrawn from the liquid and given a vapor treatment for a predetermined length of time.

A further object of this invention is to provide apparatus for automatically subjecting material to a softening process so that with a known quality of material any desired quantity may be softened to the desired degree, and each batch of material will have the same degree of softness so that it may be formed or shaped as may be desired.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a fragmentary detail front elevation of a material treatment apparatus constructed according to an embodiment of this invention, the device being partly in section.

Figure 2 is a view similar to Fig. 1 but showing the immersion controlling means and the vapor chamber with the cover thereof removed.

Figure 3 is a detail side elevation of the dipping basket and the supporting means therefor.

Figure 4 is a sectional view taken on the line 4—4 of Fig. 3.

Figure 5 is a front elevation of the guide member.

Figure 6 is an end view of the guide member shown in Figure 5.

Figure 7 is a side elevation of the guide member shown in the two preceding figures.

Figure 8 is a front elevation of the slide.

Figure 9 is a section taken on the line 9—9 of Figure 8.

Figure 10 is an elevation of the left side of the slide shown in Figure 8.

Figure 11 is a side elevation of the sliding rack or gear.

Figure 12 is an end view of the sliding rack of Figure 11.

Figure 13 is an elevation of the sliding rack looking at the left side of Figure 11, and

Figure 14 is a section taken on the line 14—14 of Figure 1.

Referring now to the drawings, and first to Figs. 1 to 4 inclusive, the numeral 10 designates generally a housing provided with a lower submersion chamber 11 and a vapor chamber 12 disposed thereabove. The chamber 11 is adapted to have a liquid placed therein of suitable character for treatment of the material used in making the caps of shoes.

A channeled guide member 13 shown best in Figures 3 and 5 to 7 extends through the vapor chamber 12 and down into the liquid chamber 11, and a slide 14 best shown in Figures 4 and 8 to 10 engages this guide 13, and is provided at the upper end thereof with a handle or knob 15 by means of which the slide 14 may be pushed downwardly.

The slide 14 is provided with a rack portion 16 and a longitudinally extending recessed portion 17 extends downwardly from the lower end of the rack portion 16. The slide 14 is also provided with a longitudinally disposed channel 18, and in this channel a vertically movable rack 19, shown in detail in Figures 11 to 13, is disposed. The upward movement of the rack 19 is limited by a stop 20, and when in its uppermost position the rack 19 will have the teeth thereof alining with the teeth 16.

The lower end of the slide 14 is provided with an outstanding arm 21 which is slotted as at 22, and this arm 21 terminates in a vertical depending extension 23 provided with a headed pin 24. A basket or material dipping member, generally designated as 25 has a depending bifurcated arm 26 detachably engaging through the slot 22 and engaging the headed pin 24 so as to hold the basket 25 in outstanding position relative to the slide 14 as illustrated in Fig. 1. This basket 25 comprises a base or bottom 27 to which are secured a plurality of spaced apart material supporting members 28 which are preferably made from a single piece of wire bent into such a shape to properly support the sheets of material during the treatment thereof.

The channel 18 is provided adjacent the upper portion thereof with an opening 29, and a gear 30 is mounted on a shaft 31 so that the gear 30 projects through this opening 29 and meshes with the rack 16 and the rack 19. The gear 30 is connected to a suitable train of gears 32 the purpose of which is to retard rotation of the gear 33.

30, and a clock spring 30', as seen in Figure 14, is associated with the gear 30 to lift the rack 19. The gear train 32 also effects a retarding of the movement of the slide 14 for a portion of the movement thereof while the gear 30 is in engagement with the rack 16 formed on the slide.

A slide operating gear 33 mounted on a shaft 34 is opposed to the gear 30 and projects through an opening 35 in the guide 13 and meshes with rack teeth 36 provided on the side of the slide 14 opposite from the teeth 16. These teeth 36 extend for a considerable portion of the length of the slide 14. A pulley 37 is secured to one side of the gear 33, and a flexible member 38 is wound about this pulley or drum 37. A weight 39 is secured to an end of the flexible member 38 and acts to constantly draw the slide 14 and the basket 25 upwardly. A second gear train 40 is connected to the gear 33 and serves as a retarding means for this gear.

The gear 33 is provided with a depth controlling pin 41, and this pin 41 moves in the path of a pin 42, seen in Figure 3, mounted on a lever 43 which is pivotally mounted on the shaft 34 exteriorly of the housing 10. A plurality of spaced apart holes 44 are provided in the housing 10 above the arcuate slot 45, and a spring pressed knob member 46 is carried by the lever or pointer 43 and is adapted to engage in a selected hole 44 so that the pin 42 will permit only a predetermined rotation of the pin 41 and thereby regulate the downward movement of the basket 25.

A scale 47 is mounted on the housing 10, and the pointer or lever 43 swings across this scale so that the operator of the device may predetermine the depth to which the basket is to be lowered. A second pointer 48 is mounted on the extended end of the shaft 34 and swings across a dial or scale 49 to indicate the position of the sliding rack 19.

A wall 50 is secured beneath the movable basket 25, and when the basket 25 is within the vapor chamber 12 this wall divides the vapor chamber from the liquid or immersion chamber 11 (see Fig. 2).

In the use and operation of this device, the sheets of material are placed in the basket 25 between the supports 28, which supports serve as a means to maintain the sheets in spaced apart relation so that each sheet will be completely immersed or covered by the liquid. The slide 14 is then pushed downwardly to the limit permitted by the adjustable stop pin 42, and when the slide is in its lowermost position the gear 30 will mesh with the teeth 16.

When the slide 14 is released by the operator, the weight 39 will immediately begin to lift the basket upwardly, and the upward movement of the basket 25 will be retarded by the gear train 40, and also by the gear 30 and the gear train 32, so that the initial upward movement of the slide 14 will be relatively slow, and this movement will obtain until the gear 30 rides off of the teeth 16, whereupon the slide 14 will be retarded by only the gear train 40 and will thus move upwardly at a faster rate. The gear 30 is constantly in mesh with the sliding gear or rack 19, and when the slide 14 moves independent of the gear 30 the rack 19 will be caused to move upwardly at a slower rate than the slide 14 and so will be relatively lowered in the guide groove 18 but gradually moves up in the slide 14 and engages the stop 20 thereon after a predetermined time interval.

When the basket 25 rises to the vapor chamber

12 the movement thereof will stop, but the timed movement of the sliding rack 19 will continue until this rack strikes the stop 20. At this time the pointer 48 will indicate this fact on the dial 49 so that the operator of the device will know 5 that the time of the vapor treatment has expired. Each downward movement of the slide 14 will wind the spring associated with the gear 30 in addition to winding up the weight 39 so that it is only necessary for the operator to set the 10 pointer 43 for the desired immersion, and then watch the pointer 48 so as to see when the time of vapor treatment has expired, it being understood that the dial 49 is provided with suitable indicia to show the immersion period and also 15 with suitable indicia to show the vapor period, and if desired a suitable signal may be connected to this pointer 48.

It is obvious that various changes and modifications may be made in the details of construction 20 and design of the above specifically described embodiments of this invention without departing from the spirit thereof, such changes and modifications being restricted only by the scope of the following claims:—

What is claimed is:

1. A material treatment means comprising a casing, an immersion chamber in the casing, a vapor chamber in the casing above the immersion chamber, an article supporting member, 30 means for mounting the member normally in the vapor chamber for movement from one chamber to the other, and progressively operated means for returning the member from the immersion chamber to the vapor chamber at varying speeds. 35

2. A material treatment means comprising a casing, an immersion chamber in the casing, a vapor chamber in the casing above the immersion chamber, an article supporting member, a slide secured to the member, means for guiding said 40 slide, and progressively operated means engageable with the slide for moving the member from the immersion chamber to the vapor chamber at varying speeds.

3. A material treatment means comprising a 45 casing, an immersion chamber in the casing, a vapor chamber in the casing above the immersion chamber, an article supporting member, a slide secured to the member, guide means for the slide, means active upon movement of the member into 50 the immersion chamber for moving the member out of the immersion chamber at a predetermined rate of speed, and means active when the member has reached a predetermined point in its movement out of the immersion chamber for varying 55 the speed of the movement of the member into the vapor chamber.

4. A material treatment means comprising a casing, an immersion chamber in the casing, a vapor chamber in the casing above the immersion chamber, an article supporting member, means for reciprocably supporting the member for movement from one chamber to the other, timed means active on movement of the member into the immersion chamber for controlling the 60 movement of the member in the direction of the vapor chamber, and signal means active upon movement of the member to indicate the operation of the device with relation to its cycle.

5. A material treatment means comprising a 70 casing, an immersion chamber in the casing, a vapor chamber in the casing above the immersion chamber, an article supporting member, means for supporting the member normally in the vapor chamber for movement from the vapor chamber 75

5 to the immersion chamber, gravity operated means for returning the member from the immersion chamber to the vapor chamber, and means active when the member has been moved to the immersion chamber for retarding the return of the member by varying amounts whereby the return takes place at varying speeds.

6. A material treatment means comprising a casing, an immersion chamber in the casing, a vapor chamber in the casing above the immersion chamber, an article supporting member, means for supporting the member normally in the vapor chamber for movement from the vapor chamber to the immersion chamber, weighted means for 10 returning the member from the immersion chamber to the vapor chamber, and means active when the member has been moved to the immersion chamber for retarding the return of the member, said latter means being inactive at a predetermined point in the return of the member from the immersion chamber to the vapor chamber.

7. An apparatus for treating materials with liquids and vapors comprising a container adapted to receive a quantity of liquid in its lower portion and to contain vapor in its upper portion, a support for holding the material in separated position, reciprocating means for the support to hold the same normally raised and to carry the latter into and out of the upper and lower portions of 15 the container, two-stage return control means for 20 said reciprocating means to retard the movement

of the support out of the lower portion of the container to impregnate thoroughly the material with the liquid and to accelerate the movement of the support into its normal raised position in the container after leaving the liquid for subjecting the material to the vapor. 5

8. An apparatus for treating materials with liquids and vapors comprising a container adapted to receive a quantity of liquid in its lower portion and to contain vapor in its upper portion, a support for holding the material in separated position, reciprocating means for the support to hold the same normally raised and to carry the latter into and out of the upper and lower portions of the container, a toothed rack on said means, a gear wheel mounted to engage said rack and to be rotated by reciprocation of said means, gravity actuated means for rotating said gear wheel, said gravity actuated means being placed in operative position when the reciprocating means is depressed and operating to raise the said means thereafter, a stop on said gear wheel, and adjustable means including a member for engagement with said stop on the gear wheel adapted for positioning at various positions to place said member at various positions in the path of the stop to limit the rotation of said gear wheel and thereby limit the degree of movement of the said reciprocating means. 10 15 20 25
